UNITED STATES PATENT OFFICE.

OSCAR C. BERNARD, OF EL PASO, TEXAS.

PROJECTING-MACHINE.

1,318,255.

Patented Oct. 7, 1919.

Application filed September 22, 1916. Serial No. 121,658.

To all whom it may concern:

Be it known that I, OSCAR C. BERNARD, a citizen of the United States, residing at El Paso, in the county of El Paso and State 5 of Texas, have invented new and useful Improvements in Projecting-Machines, of which the following is a specification.

This invention relates to advertising machines or devices the object in view being to 10 simplify and improve the construction set forth in my prior Patent No. 1,069,521 dated August 5, 1913, to the end that the mechanism involved will be productive of greater accuracy and reliability thus insuring the 15 proper working of the entire mechanism and reducing to a minimum the liability of any part of the mechanism getting out of order.

Another object in view is to adapt a machine of the class referred to to be used in 20 several different ways and for several different purposes, as for example, to successively exhibit or display opaque surfaces, post cards, printed matter and the like; to exhibit 25 such cards, surfaces or matter during the day time or after dark.

Another important object of the invention is to provide in connection with a revoluble magazine containing slides adapted 30 to be projected therefrom, and a display receiver associated therewith, driving mechanism for actuating said magazine with an intermittent movement, and novel means for causing said mechanism to operate continuously 35 without any attention on the part of the operator, or to be controlled by an operator so that the periods of rest or dwell between the exhibition of the slides, may be varied at the will of the operator, thus adapting the machine particularly for lecture purposes, the operation of the machine 40 being controlled at any desired distance therefrom by the lecturer.

With the above and other objects in view, 45 the invention consists in the novel construction, combination and arrangement of parts, as herein described, illustrated and claimed.

In the accompanying drawings:—

Figure 1 is a side elevation, partly in section, of the machine of this invention, showing the display receiver in its normal slide displaying position.

Fig. 2 is a side elevation of the machine taken opposite the side shown in Fig. 1.

Fig. 3 is a front elevation thereof.

Fig. 4 is a rear elevation of the same.

Fig. 5 is a vertical longitudinal section through the machine showing the switch mechanism and other parts in elevation.

Fig. 6 is a fragmentary vertical section 60 through the magazine showing the relation of the feed dog thereto.

Fig. 7 is a fragmentary section through the timing mechanism.

Fig. 8 is a fragmentary elevation showing 65 the latch mechanism for the receiver, looking from the inner side of the frame.

Fig. 9 is a view partly in section and partly in elevation of the trip mechanism.

Fig. 10 is a fragmentary vertical transverse section illustrating a portion of the slide projecting means.

Fig. 11 is an inside elevation of the same showing one of the slides and the magazine shaft in section.

Fig. 12 is a diagrammatic view of the switch mechanism showing the wiring therefor.

Fig. 13 is a detail perspective view of one of the slides or holders.

Fig. 14 is a plan view of the lamp holder.

Fig. 15 is a fragmentary vertical section showing the magazine locking means.

Fig. 16 is a fragmentary vertical section 85 of the slide displaying receiver.

Referring to the drawings A designates generally a frame, certain parts will be hereinafter particularly referred to. 1 designates the base of the frame and 2 a pair of oppositely arranged uprights which support 90 the shaft 3 of a revoluble magazine designated generally at B and adapted to carry a circular series of radially movable slides C the major portion of each of which is adapted to be projected beyond the periphery of 95 the magazine into a receiver designated generally at D where said slides are displayed in a manner hereinafter more particularly referred to.

The magazine comprises two disk shaped 100 heads 4 arranged in spaced relation to each other and mounted upon the shaft 3, the said plates being formed with radial guide ways 5 arranged in transversely aligned pairs to

receive and guide the opposite edges of the slides or holders above referred to. Located outside of the heads 4 are annular bands or hoops 6 which, as shown in Figs. 3 and 4 are spaced slightly from the heads 4 but fixedly connected thereto by means of fasteners 7 such as rivets or the like. These bands or hoops serve to rigidly connect the portions of the heads 4 separated by the 5 guide ways 5. Tie-bolts 8 connect the heads 4 and the annular bands 6 at intervals. The bands 6 are formed in their outer peripheries and in line with the guide ways 5, with notches 9 forming shoulders which are successively engaged by a feed dog 10 best shown in Fig. 6, said dog having a lip 11 to enter the notches 9 and the dog being pressed toward its engaging position by means of a spring 12 which rests at its free extremity 10 against the periphery of one of the magazine heads and the adjacent band 6. The feed dog 10 is carried by a pivot 13 on a feed dog carrier 14 shown in the form of an arm which is journaled at one end on the 15 shaft 3 and provided beyond the pivot 13 with a projecting portion 15 having a dwell face 16 the function of which will appear.

In order to prevent the slides or holders from dropping out of their guide ways in 30 the magazine at the lower part of the latter, I provide a guard or track rail 17 one end of which is connected by a fastener 18 to a cross bar 19 which is terminally fastened at 20 to arcuate extensions 21 of the frame of the machine. The other end of the rail 17 is fastened at 22 to another cross bar 23 terminally fastened to vertical bars 24 of the frame, the frame members 24 being connected by arcuate frame pieces 25 to upright 35 frame pieces 26 and also to the base 1, the frame pieces 25 serving as supports for the shaft 27 of the driving mechanism herein-after more particularly described.

The driving mechanism for imparting motion to the magazine, is shown as comprising a motor 28 which drives through a belt 29 a worm shaft 30 the worm 31 of which drives a worm wheel 32 on a shaft 33 supported by the arcuate frame pieces 25. A pinion 34 on the 40 shaft 33 drives a large wheel 35 which constitutes the master gear or wheel of the driving mechanism. The wheel 35 is provided upon one side thereof with a projection 36 shown in the form of a pin or stud which at 45 a certain point in the travel of the wheel 35 comes in contact with the curved end portion of a slide operating lever 37 fulcrumed at 38 on one of the frame pieces 24 above described. Fast on the shaft 27 is an arm 39 50 carrying at its extremity a projection 36' which performs the same function as the projection 36 just referred to, said projection 36' co-operating with another lever 37 at the opposite side of the machine frame 55 and corresponding in all respect with the

first named lever 37. The levers 37 are connected by pivotal links 40 to slide controlling levers 41 which are fulcrumed between their ends on journals 42 on the uprights 2 of the frame. The levers 41 are also connected by pivotal links 43 to a pair of slide projecting members 44 shown in the form of levers pivotally supported at 45 on the arcuate extensions 21 of the frame. 70

By now referring to Figs. 10 and 11 in 75 connection with Fig. 1 it will be seen that each of the slide projecting members 44 is formed with a rounded end portion 45 which slides through a guide way 46 in a vertically movable runner 47. This runner serves as 80 a vertically movable support for the slides, being provided with an upwardly extending finger 48 which lies directly under one of the bottom corners of the slide or holder as shown in Fig. 10. Each runner is also 85 forked or provided with arms 49 which embrace a vertically extending guide 50 secured to the inner side of the adjacent upright 2. It will now be understood that as the slide projecting members 44 move 90 upwardly from the position shown in Fig. 11, the end portions 45 thereof slide through the guide ways 46 of the runners while moving said runners in an upward direction and thereby elevating or projecting one of 95 the slides or holders from the magazine into the display receiver above. This upward movement of the projecting members 44 is caused by the projections 36 and 36' coming in contact with the levers 41 which 100 are formed with notches bounded by inclined curvilinear faces 51 and 52 against which said projections on the wheel 35 ride while said wheel continues to turn. As the projections 36 and 36' depress the ends of the 105 levers 41 adjacent to the wheel 35; the opposite ends of said levers, through the medium of the links 43 swing the slide projecting members upwardly. The parts referred to remain in this position until the wheel 35 110 has made about three-fourths of a revolution when the projections 36 and 36' come in contact with the levers 37 and rock said levers on their fulcrsa. Then through the mediums of the links 40, the end portions of 115 the levers 41 adjacent to the wheel 35 are swung upwardly and by means of the links 43, the slide projecting members 44 are swung downwardly. This permits the runners to travel in a downward direction and lower 120 the slide supported thereby into its guide ways 5 in the magazine. In the travel of the projection 36, the latter comes into contact with and depresses the adjacent end of the feed dog carrier 14 thereby causing the 125 dog 10 to turn the magazine a distance equal to the space between two adjacent notches 9, thereby moving the slide just exhibited out of line with the receiver, and moving the succeeding slide into position to be projected 130

upwardly into the receiver. The dwell face 16 of the feed dog carrier enables the dog 10 to be held at the lower limit of its movement a sufficient length of time to allow the slide 5 projecting members 44 to reach the upper limit of their movement and fully project a slide. As soon as the projection 36 passes beyond the extremity of the dwell face 16, a spring 53 acting on the feed dog carrier 10 14 serves to return the feed dog 10 to the next succeeding notch 9 of the magazine. This provides for the intermittent movement imparted to the magazine.

The levers 41 are shown as provided with 15 arcuate dwell faces 54 concentric with the axis of the shaft 27 against which the projections 36 and 36' ride after the feed dog carrier 14 is released and carried upwardly by the action of the spring 53. In this way 20 the levers 41 are held in the position illustrated in Figs. 1 and 2. This serves to prevent the slide projecting members 44 from moving downwardly to any extent. As an additional safe-guard, I employ in connection 25 with the magazine, locking mechanism for holding the magazine stationary when each slide or holder is in line with the receiver. The lock is shown in the form of a vertically movable sliding member 55 having a shoulder 56 against which the adjacent lever 41 is adapted to strike in the downward movement of that arm of the lever to which the link 43 is connected. The member 55 is provided at its lower end with 30 an inwardly extending lip 57 which is normally held in engagement with one of the guide ways 5 of the magazine by means of an underlying spring 58 thereby preventing any possibility of the magazine turning at 35 an inopportune moment. When the slide projecting members 44 approach the lower limit of movement and the slide or holder has moved downwardly into its normal position in the magazine, the lever 41 acting 40 against the shoulder 56 throws the locking lip 57 out of engagement with the magazine, leaving the same free to be acted upon by 45 the feed dog 10 for the purpose above described.

50 As an additional safeguard to prevent rotation of the magazine, a spring detent 59 is fastened to the guard rail 17 and formed with an offset 60 to engage a cross rod 61 terminally held by lugs 62 on the levers 41. When said levers reach the lower 55 limit of their movement, the detent 59 snaps into engagement with the cross rod 61 thus holding the lever mechanism until the projections 36 and 36' again depress the adjacent 60 ends of the levers 37 for the purpose above set forth.

In order to provide for stopping the motor and thereby of course terminating for the time being the operation of the device as 65 the whole, I provide a motor switch 63

which is diagrammatically shown in Fig. 12 as comprising two yielding contacts 64 and 65 and a slideable contact or bridge piece 66 having an off-set or lug 67 adapted to engage in either one of a pair of depressions 68 and 69 in the contact 65, this being for the purpose of holding the sliding contact 66 either in or out of engagement with the contact 63, the object of course being to make and break the circuit. The switch 75 member 63 is shown as provided with a head 70 which, as best illustrated in Fig. 9, is attached to and actuated by a slideable switch operating member 71 from which extends a plunger rod 72 having a head 73 by 80 means of which the member 71 may be pushed in a direction to close the circuit of the switch 63 and thereby start the motor. The sliding member 71 is mounted in a suitable casing 74 together with a pneumatic 85 cylinder 75 in which operates a plunger 76 which is connected at 77 to an arm 78 of the member 71. A flexible tube 79 equipped with a hand pressure bulb communicates with the cylinder 75 so that the 90 operator, standing at any desired distance from the machine, may actuate the sliding member 71 by air pressure, thereby closing the switch 63 and starting the motor which drives the magazine and other mechanism 95 hereinabove described. After the motor is started in the manner described either by compressing the hand bulb 80 or pressing inwardly on the head 73, the motor will operate continuously.

To provide for cutting out the motor and interrupting the operation of the machine, a trip 81 is pivotally mounted at 82 on the sliding member 71 and is formed with a lip or projection 83 against which another projection or pin 84 on the wheel 35 is adapted to strike as indicated in Fig. 5. The trip 81 is pivotally mounted on the member 71 so that it may turn to the tripping position shown in Fig. 5 or to a non tripping position as shown in Fig. 9. When in a tripping position as shown in Fig. 5 in each revolution of the wheel 35, the pin or projection 84 will push against the lip 83 of the trip and shift the sliding member 71 105 so as to break the circuit of the motor switch 63 by actuating the slide contact 67 away from the contact 64. When the motor is started again, the wheel 35 again starts to turn in the same direction as before and keeps turning until the projection 84 again operates the trip 81. After the circuit is broken the projection 84 overrides the trip 81 as the motor is overrun. The motor is started again by actuating the slide 71 in 110 the opposite direction, by finger pressure on 73 or by compressing bulb 80, assisted by the spring 80' which of itself is too weak to actuate the slide 71 to close the circuit, on account of the resistance to said closing 115 120 125 130

movement produced by the spring contact 87 (see Fig. 12).

- In addition to the motor switch just hereinabove described I also employ a combined 5 light and motor switch 85 which is diagrammatically shown in Fig. 12, being similar to the motor switch 63 in that it comprises the spring contacts 86 and 87, the sliding contact 88, and the off-set or lug 89 on the member 88 which engages one or the other of depressions 89 and 90 in the contact 87 for making or breaking the circuit. The 10 sliding contact 88 is provided with end portions 91 which are engaged by the arms 92 and 93 of a plunger bar 94 having at one end a head 95 by means of which it may be pressed in one direction by the operator for the purpose of shifting the switch member 88 in a direction to complete the circuit. 15 The plunger bar has its opposite end expanded to form a shoulder 96 adapted to be engaged by a pin or projection 97 on a timing wheel 98 to provide for automatically operating the switch member 88 to 20 cut off the current from the motor at a predetermined time. The wheel 98 is mounted in a suitable supporting casing 99 and is provided on its periphery with ratchet teeth 100 engaged by a pawl 101 attached to a pawl carrier 102 which is 25 journaled on the shaft 103 of the wheel 98. The adjacent band 6 of the magazine is formed at one point with a depression or notch 104 as shown in Fig. 1 to allow 30 the pawl 101 to be retracted or thrown back by means of a spring 105, backward movement of the wheel 98 being prevented by a detent 106 mounted on the frame or casing 99. The shaft 103 has mounted on one 35 end thereof a pointer or indicator 107 which sweeps around a timing dial 108 suitably graduated to indicate periods of time such as hours and fractions thereof as clearly indicated in Fig. 1. The indicator or pointer 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 one of said stop shoulders forming a finger piece to be used for the purpose of rocking the latch out of engagement with the arm 21. By simultaneously operating both latches 5 123, the receiver D may be lowered from a vertical position to a horizontal position so as to lie between the horizontal bars or members 114 of the frame as shown in Fig. 5, for packing or transportation purposes. The 10 lamp 109 is removably screwed into a socket 127 carried by the arm 110 so that it may be removed when desired. 128 designates a support located under the magazine and upholding the center portion of the guard rail 15 or track 17, and 129 designates a slide righting member which prevents the slides from tilting and binding in their guide ways in the magazine as they sweep around the lowest point of their circuit.

20 One of the slides or slide holders is illustrated in detail in Fig. 13. Said slide or holder comprises a plate like body 130 having a central opening or orifice 131 and flanges 132 and 133 extending along parallel 25 marginal edges thereof to receive guide and hold cards lantern slides and the like. The flange 132 is bent so as to form a shallow member 134 closed at one end by means of a stop or end wall 135 and open at the other 30 end to receive a card for example. The flange 132 is also formed with a deeper portion 136 of less length than the member 134 and terminating in a closed end or stop shoulder 137, the deeper and shorter portion 35 136 of the flange being designed to receive a thicker glass or transparent lantern slide. Adjacent to the receiving end, the flange 132 is cut away at 138 to receive a bowed friction clasp 139 shown in the form of a 40 spring having one end attached at 140 to said flange. The bowed portion of the clasp is so positioned that it will frictionally engage and hold either a card or a lantern slide. The extreme edges or margins 141 of the 45 slide or holder C are slidingly received in the guide ways 5 of the heads of the magazine as hereinabove noted. 142 represents an auxiliary handle or knob on the plunger bar 94 for the convenience of the operator in 50 stopping and starting the motor and turning on or off the lamp 109.

The slide or holder which is movable up and down in the receiver only and which is controlled in its movements by the successive 55 magazine slides or holders, is provided with flanges 132 and 133 on both faces thereof, said flanges being identical with those above described in connection with the magazine slides or holders. By providing 60 two sets of flanges as stated, the cards or slides may be inserted under the flanges and thereby arranged at either side of said additional or double slide as shown in Fig. 16. The said double slide is provided ad-

jacent to the opposite vertical side with 65 shoulders 173 which as said slide moves downwardly, come in contact with other shoulders 175 on the uprights of the receiver. This prevents the slide or holder referred to from descending far enough to 70 engage the magazine and interfere with the intermittent rotated movement thereof.

I claim:

- An advertising device comprising a frame, a revolving magazine provided with 75 guideways, driving means for imparting intermittent movement to said magazine, slides movable in said guideways, and means for projecting said slides from the magazine while the latter is at rest, said driving means 80 embodying an electric motor, an energizing circuit for said motor, and a circuit-breaking switch automatically operated to cut out the motor each time a slide is projected from the magazine. 85

2. An advertising device comprising a frame, a revolving magazine provided with guideways, driving means for imparting intermittent movement to said magazine, slides movable in said guideways, and means 90 for projecting said slides from the magazine while the latter is at rest, said driving means embodying an electric motor, an energizing circuit for said motor, and a circuit-breaking switch automatically operated 95 to cut out the motor each time a slide is projected from the magazine, and manually controlled means for closing said switch.

3. An advertising device comprising a frame, a revoluble magazine having guideways, slides movable in said magazine, driving means for imparting intermittent motion to said magazine, and means for projecting the slides from the magazine while the latter is at rest, said driving 100 means embodying a motor, a wheel driven thereby, a feed dog actuated by said wheel to move the magazine with a step by step movement, the slide projecting means embodying a slide projecting member, operating connections between the latter and said wheel, and a friction lock engaging an element of said connections to sustain a slide 105 in its projected position. 110

4. An advertising device comprising a 115 frame, a revoluble magazine having guideways, slides movable in said magazine, driving means for imparting intermittent motion to said magazine, and means for projecting the slides from the magazine 120 while the latter is at rest, said driving means embodying a motor, a wheel driven thereby, a feed dog actuated by said wheel to move the magazine with a step by step movement, the slide projecting means embodying a slide elevating and lowering runner, a projection on said wheel and two levers in the path of said projection, oper- 125

atively connected with said runner, one of said levers acting to push the runner upwardly and the other acting to pull the runner downwardly.

5. In an advertising device of the class described, a slidable holder, comprising a flat body having a slide display opening through the same, parallel flanges on one

face of said body one of which is offset to form a guideway for cards and slides of different thicknesses, and a yieldable friction clasp for holding such cards and slides in proper relation to the body.

In testimony whereof I affix my signature.

OSCAR C. BERNARD.
